UNITED STATES PATENT OFFICE.

HENRY M. REICHENBACH, OF NEW YORK, N. Y.

CARBURETER.

No. 854,604.

Specification of Letters Patent.

Patented May 21, 1907.

Application filed August 28, 1905. Serial No. 276,161.

To all whom it may concern:

Be it known that I, HENRY M. REICHENBACH, a citizen of the United States, residing at New York, in the county of New York and State of New York, have invented certain new and useful Improvements in Carbureters; and I do hereby declare the following to be a full, clear, and exact description of the invention, such as will enable others skilled in the art 5 to which it appertains to make and use the same.

My invention relates to improvements in devices for the storage of liquid fuel, and the supplying of carbureted air to internal combustion engines, the storage tank acting as a combined storage tank and carbureter, there being no free fluid in the storage tank, thereby eliminating the danger of leakage of such free fluid in the vehicle, vessel or car in 15 which the engine is used. The fuel is supplied to the tank at intervals, and the supply is stored at some point separate from the apparatus. The tanks are of such capacity that they will hold by absorption a sufficient 20 quantity of fuel for trips away from the basic supply—from five to fifty gallons, or more, as is necessary.

The object of my invention is to produce a perfectly safe carbureter, in which all the 25 fuel is contained in a mass of absorbent material, which carbureter may be connected with a source of supply at intervals.

Other objects are to provide a carbureter in which volatilization is readily effected, in 30 which means for varying the amount of fuel used, is provided, and in which provision is made to compensate for the refrigeration caused by the volatilization of the fuel.

With these objects in view my invention 35 consists in the construction and combinations of parts as hereinafter described and claimed.

In the accompanying drawings Figure 1 is a longitudinal vertical section of my improved carbureter. Fig. 2 is a horizontal cross section thereof taken just below the top. Fig. 3 is an end elevation partly broken away, Fig. 4 shows in detail the means for distributing the fuel. Fig. 5 is side view 40 of the carbureter and the tank for filling the same.

a represents the main casing preferably made of metal, across which near the top thereof extends a metal plate *b* having 45 spring edges *c* which hold the same in posi-

tion. This plate is perforated as shown at *d*, and around each perforation the edges of the plate are turned upwardly, as shown at *e* to prevent the gasoline or other fuel from running down through these perforations. 60 Near the outer edges of two sides of the plate *b* it is provided with perforations *f* through which the fuel drips down through the carbureting casing.

Parallel to the plate *b* are a series of plates *g* similar in construction to the plate *b* except that they extend less than half way across the casing *a* and are provided on the inside with bent edges *h* which rest against the wall *i*, the outer edges *c* in connection 70 with the edges *h* serving to hold the plates in position. The construction is the same on both sides of the carbureter, leaving an open chamber between the walls *h*.

Below the plate *b*, and between the plates *g*, 75 are located a number of layers of absorbent material *j*, which receive the liquid fuel as it drips through the perforations *f* on the outside edges of the plates and conducts it toward the center. The plates and the layers 80 of absorbent material are all perforated, the perforations being located in line with each other so that the passages *e* extend from nearly the top to the bottom of the casing *a*. Any suitable absorbent material may be 85 used, but I prefer to use dry wood felt.

k represents the air inlet pipe, which is connected to the external air and is provided with a valve *m*. This pipe *k* enters one end of the chamber *a* and passes nearly the 90 whole length thereof, as shown in Fig. 1, being provided with a number of perforations *n* through which the oil is discharged onto the top plate *b*, which plate has a central bead *o* to direct the liquid fuel to either side of the 95 carbureter casing. The fuel inlet pipe delivers directly into the air pipe *k*, as herein-after described.

p represents the outlet pipe for the carbureted air which is provided with a series of 100 perforations *q*. This pipe leads to the engine and is controlled by a valve *r* operated by the link *s*. This valve is adjustable by means of the set screw *t*.

u represents a pipe connected with the external air which joins the pipe *p* in a union joint *v*, which serves as a mixing chamber. The pipe *u* is provided with a valve *w*.

By the means described, if the carbureted air in the pipe *p* contains too large a portion 110

of fuel additional air may be mixed therewith to make the proper mixture. The valve *w* is operable by a handle *x*, and this handle, by means of a lever *y* and link *z*, is connected to the link *s*, so that the movement of the handle *x* simultaneously operates the valves *r* and *w*.

1 represents the exhaust pipe leading from the engine. Connected to this pipe are pipes 3 and 4 which pass into the chamber 5 between the walls *i*, the pipes 3 and 4 and the chamber 5 forming a by-pass, whereby the whole or a portion of the exhaust gases may be admitted into the inner part of the carbureter to supply heat thereto to compensate for the loss of heat caused by the evaporation of the fuel.

The pipe 1 is provided with a valve 6, the movement of which causes a greater or less amount of the exhaust gases to pass through the carbureter, or permits them to pass freely through the pipe 1. This valve is operated by a handle 8 which is connected by a link 7 with the link *z*, so that the valve 6 is operated simultaneously with the valves *r* and *w* by the movement of the single lever *x*.

Each of the valves *r*, *w* and 6 is provided with a set screw, such as *t*, so that they may be adjusted relatively to each other. In winter, for example, it is desirable that a larger proportion of the exhaust should pass through the carbureter, than in summer, and furthermore, under certain conditions of weather, or with certain kinds of fuel, different quantities of air must be drawn in through the pipe *u*. All this is determined by experiment and the set screws *t* adjusted, and after this adjustment has been made a movement of the lever *x* is all that is required to control the richness of the carbureted air mixture.

The heating of the carbureter may also be accomplished by means of the cooling water from the cylinders, instead of by the exhaust gases, in which case the pipes leading the hot water from the cylinder, pass into the chamber 5 and then connect with the cooler.

My improved carbureter is also provided with a safety filling device. Entering the end of the tube *k* is a fuel pipe 9 provided with a valve 10 and a funnel 11. From the bottom of the carbureting casing extends a drainage pipe 12 provided with a valve 13, and the end of this pipe is made conical. A lever 14 is used for opening or closing the valve 10, and a link 15 connects this lever with the lever 16, which operates the valve 13, so that the valves 13 and 10 are opened and closed simultaneously.

17 represents a fuel supply pipe, the upper end of which is curved.

18 represents a drainage pipe having a conical top which is adapted to fit tightly over the end of the discharge pipe 12 of the carbureter proper. The pipes 17 and 18 are movably connected together by the fitting

20, which is rigidly attached to the pipe 18, and through which the pipe 17 slides, when drawn downward by the spring 21, which is attached at one end to the fitting 20, and at the other end to a projection 19 on the pipe 17.

Fig. 5 represents the tank in the position to fill the carbureter.

25 represents the tank provided with a projecting boss or fitting 22 through which the pipes 17 and 18 pass.

23 represents (in dotted lines) a pump, having an operating handle 24 projecting up through the fitting 22, said pump delivering into the lower part of the pipe 17. The lower parts of the pipes 17 and 18 may be flexible, if desired.

One distinct feature of my invention is that the carbureter is not directly connected to the fuel tank, but is supplied with fuel only at intervals, and this is an important feature as regards the safety of the device. Furthermore, the air in the pipes *k* and *u* is carried to a higher point than usual, so that if the fuel should volatilize too rapidly through overheating of the carbureter, it would either be condensed in these pipes or delivered to the external air. In no case could there be an escape of carbureted air into the compartment containing the engine. This is a very valuable feature for submarine boats, passenger cars, automobiles, and all other forms of conveyances. In a submarine boat the air inlets will, of course, necessarily connect with the air inside of the boat, but in such a case a condenser coil or other pipe extension should be used to prevent any backward movement of the vapor from the carbureter.

Another distinct feature of my invention is the provision of the heating chamber and the location of the same in the mass of absorbent material or in contact therewith, and arranged to deliver heat to the plates separating and extending into the absorbent material. With the arrangement described, the liquid is delivered to the absorbent material at points remote from the heater and moves through the absorbent material in directions opposite to the flow of heat from the heater along the plates, separating the absorbent material. The result of this arrangement is that the liquid will vaporize as it moves toward the heater, and the lighter hydrocarbons will be driven off first and at points remote from the heater, while the heavier hydrocarbons will move along until they reach points where the temperature is so high, owing to the proximity of the heater, that they also will be vaporized.

One of the chief objections to many of the carbureters now in use is that they cannot be used without considerable danger of explosions, and it is now regarded as highly desirable, and even indispensable, to have the

safety factor of carburetors very high. This advantage is fully secured by the present invention.

Having thus described my invention, what I claim and desire to secure by Letters Patent, is:—

1. The combination of a casing provided with a heating chamber, said casing having absorbent material therein, the whole forming a carburetor, means for heating said chamber, means for mixing the carbureted air passing out of said carburetor with additional air, and means for simultaneously controlling the amount of carbureted air passing out of said carburetor, the amount of air mixed with said carbureted air, and the amount of heat supplied to said carburetor, substantially as described.
2. The combination of a carburetor provided with a heating chamber, a valved pipe connection for supplying hot fluid to said heating chamber, a valved delivery pipe for the carbureted air, a valved pipe connected with said delivery pipe, and means for simultaneously operating the valves in the three sets of pipes, substantially as described.
3. The combination of a carburetor provided with a heating chamber, pipe connections for supplying heated fluid to said chamber, a valve located in said pipe connections, a delivery pipe for the carbureted air, a valve in said delivery pipe, a pipe leading from the external air to said delivery pipe, a valve in said last mentioned pipe, connections whereby said three valves may be operated simultaneously, and means for adjusting each of said valves, substantially as described.
4. The combination of a casing provided with a heating chamber, said casing having absorbent material therein, the whole forming a storage carburetor, a carbureted air delivery pipe, a valve therein, a pipe leading from the external air to said delivery pipe for diluting the carbureted air, a valve in said last-mentioned pipe, connections whereby said valves may be simultaneously operated, and means for separately adjusting each of said valves, substantially as described.
5. The combination of a carburetor provided with a heating chamber, pipe connections for supplying hot fluid to said heating chamber, a valve mounted in said pipe connections, a delivery pipe for the carbureted air, a valve in said delivery pipe, connections whereby said valves may be simultaneously operated, and means for separately adjusting each of said valves, substantially as described.
6. In a carburetor, the combination of a casing, metal partition plates provided with spring edges secured in said casing, absorb-
- ent packing located between said plates, said plates and packing being provided with perforations registering with each other forming air passages, and said plates being provided with perforations for the circulation of the liquid fuel, substantially as described.
7. In a carburetor, the combination of a casing provided with internal plates and walls forming a central heating chamber, metal plates provided with spring edges located between said casing and the internal walls, absorbent packing between said metal plates, said plates and packing being provided with perforations which register with each other, thereby forming air passages, and said metal plates being provided with perforations for the circulation of the liquid fuel, substantially as described.
8. The combination of a carburetor and safety devices for filling the same, consisting of supply and drainage pipes connected to said carburetor, a valve located in each of said pipes, connections for simultaneously operating said valves, a fuel tank and supply and drainage connections on said fuel tank detachably engaged with the supply and drainage pipes on said carburetor, substantially as described.
9. In a carburetor, the combination of a casing, a metal plate, provided with a central bead, located in the upper part of said casing, a perforated air pipe extending into said casing and located over said central bead, and a fuel pipe delivering into said air pipe, substantially as described.
10. In a carburetor, the combination of a casing, a metal plate extending across said casing near its top and secured therein by spring edges, said plate being provided with a central longitudinal bead, a perforated air inlet pipe entering said casing and located above said bead, and a fuel pipe entering one end of said air inlet pipe, substantially as described.
11. In a carburetor, the combination of a casing, a heating chamber therein, metal partition plates in said casing, absorbent packing located between said plates, said plates and packing being provided with perforations registering with each other, forming air passages, and said plates being provided with perforations for the circulation of the liquid fuel, and means for causing a regulated flow of hot exhaust gases through said chamber, substantially as described.

In testimony whereof, I affix my signature, in presence of two witnesses.

HENRY M. REICHENBACH.
